UNITED STATES PATENT OFFICE.

GAETANO ALBANESE, OF RICHMOND HILL, NEW YORK.

DESIGN FOR A BARBER-POLE TOP.

Application filed January 16, 1929. Serial No. 29,636. Term of patent 14 years.

To all whom it may concern:

Be it known that I, GAETANO ALBANESE, a citizen of the United States, and residing at Richmond Hill, L.I., in the county of Queens and State of New York, have invented a new, original, and ornamental Design for Barber-Pole Tops, of which the following is a specification, reference being had to the accompanying drawing, forming part thereof.

Fig. 1 is a front elevation of a barber-pole top showing my new design, the dotted lines merely show how the same may be used.

Fig. 2 is a plan view of the design.

I claim:

The ornamental design for a barber pole top, as shown.

GAETANO ALBANESE.
